UNITED STATES PATENT OFFICE.

CARL H. BISSELL, OF SYRACUSE, NEW YORK, ASSIGNOR TO CROUSE-HINDS COMPANY,
OF SYRACUSE, NEW YORK, A CORPORATION OF NEW YORK.

ELECTRIC SERVICE-BOX.

1,360,079.

Specification of Letters Patent. Patented Nov. 23, 1920.

Application filed August 29, 1916. Serial No. 117,434.

To all whom it may concern:

Be it known that I, CARL H. BISSELL, a citizen of the United States, and a resident of Syracuse, in the county of Onondaga and 5 State of New York, have invented a certain new and useful Electric Service-Box, of which the following is a specification.

This invention relates to a combination electrical service box and appliances therein, 10 for controlling the flow of current through electric circuits, and it has for its object a particularly simple and efficient construction whereby access to the live parts within the box is prevented while the circuit is 15 closed, and is only permitted when the circuit is broken. Other objects appear throughout the specification. The invention consists in the combination and constructions hereinafter set forth and claimed.

20 In describing this invention reference is had to the accompanying drawings in which like characters designate corresponding parts in all the views.

Figure 1 is a plan view, partly broken 25 away, of one form of my invention.

Fig. 2 is an elevation of parts seen in Fig. 1.

Fig. 3 is a vertical longitudinal sectional view taken nearly centrally of Fig. 1.

30 Figs. 4 and 5 are fragmentary views illustrating, respectively, the position of the movable switch member and the door when the switch member is open and the door is closed, and when the door is open from its 35 position shown in Fig. 3.

This invention comprises generally, a box having a movable switch member therein, and means for preventing access to the interior of the box except when the switch 40 member is open. Preferably the operating means for the movable switch member is carried by the cover of the box, and a coupling connects said means and the switch member and is detachably connected to one 45 of the parts it connects when the switch member is in open position, and automatically disconnects upon opening movement of the cover.

More specifically, this invention 50 comprises, a box having two compartments arranged side by side or end to end, one compartment having a movable door, a switch located in the other compartment and including switch contacts or terminals and a 55 movable switch member, terminals located in the compartment having the door and

connected to the switch terminals and co-acting means associated with the movable switch member and the door to prevent opening of the door when the switch is 60 closed and closing of the switch when the door is open, so that at no time, is it possible to open the box without breaking the circuit through the electrical appliances therein. The box is open at one side as its top and is 65 closed by a removable cover which supports the door and also the means for operating the movable member of the switch, said means having a detachable connection with the switch member. 70

1 designates the box as a whole which is here shown as oblong in general form and as having means at one end as an internally threaded nipple 2 for connection with an electric conduit. 3 is the cover for the open 75 side or top of the box, the cover being secured in position by any suitable means as cap screws 4 and having a flange 5 extending along one edge thereof toward the bottom of the box, the flange fitting a complementary 80 cut out in the contiguous side of the box.

The nipple 2 is preferably carried by, and formed integral with a plate 6 which is secured to the end of the box in any suitable manner as by cap screws 7. This plate 6 is 85 interchangeable with a closed end plate as 8. 9 is the compartment located in one end of the box and extending to near the middle thereof. 10 designates the other compartment in which electric appliances as fuses 90 are located, the compartment 10 being located in the opposite end of the box.

12 designates the door for the fuse compartment, the door being part of the cover 3 and being hinged or mounted on a shaft or 95 axis 13 extending transversely of the cover and the box near the middle thereof. The door has a latch 14 at its free end, as a reciprocally movable bolt having a handle 15 by means of which it is moved in one direction 100 out of operative position against a spring 16, the bolt coacting with a perforated lug 17 on the cover 3.

The cover 3 curves upwardly as at 18 over the switch compartment to provide space for 105 the movement of the switch member. The top is provided with a suitable lug 19 over which the ring 20 on the door 12 may be hooked in order to hold the door 12 open.

21 is an insulating base located within the 110 box and extending into both compartments.

22 and 23 are switch contacts and ter-

minals located in the compartment 9 and mounted on the block 21.

24 and 25 are terminals located in the fuse compartment on the base 21, the terminals 5 24 being electrically connected to the switch terminals 23. The terminals 25 and the switch contacts 22 are provided with suitable binding devices 26, 27 for connection to the service wires.

10 28 is the movable switch member which carries the blades or knives 29 which are pivoted or hinged at 30 to the contacts 23, this member 28 also including a cross head or bar to which is detachably connected the 15 means for operating the switch member. Said means usually includes a rock arm 31 mounted upon a rock shaft 32 supported by and extending through the flange 5 of the cover 3 in line with the pivot 30 and having 20 a handle 33 at its outer end.

The rock arm 31 is detachably connected to the cross bar of the switch member 28 by an arm 34 extending laterally from the free end of the arm 31 and along the cross bar 25 and having a coupling formed with a U-shaped channel 35 at its free end which receives the cross bar and hence couples the arm 34 to the cross bar, the channel facing toward the axis of the switch member so 30 that the arm or the coupling thereof cannot be lifted away from the switch bar except when the switch is open (Fig. 4). The cross bar is formed with a groove 36 for receiving the sides of the channel. The cover 3 can 35 only be detached from the box when the switch member is in open position as the coupling or the U-shaped channel thereof, cannot be detached from the cross bar of the switch member 28, when the switch is in 40 any other position. Hence, a movement to displace the cover 3 when the switch member is in closed position will cause the switch member 28 to open. The cover 3 can be replaced only when the switch member is in 45 open position and for the purpose of guiding the cross bar of the switch member 28 into the U-shaped channel 35 of the coupling, the coupling is provided with an inclined extension or guide 37 on one side of 50 the channel.

The axis 32 of the switch member and the axis 13 of the door are located transversely of the box near the middle thereof, and near and parallel to each other, and coacting 55 means are provided on the operating means for the movable switch member 28 and the door 12 which means control the opening and closing of said switch member and the door. As here shown, rock arms 38, 39 are 60 associated respectively with the door 12 and the arm 31 of the switch operating means, the rock arm 38 on the door 12 extending into the path of the rock arm 39 associated with the switch member to prevent closing 65 of the switch member when the door is open

and the switch member is open, and the arm 39 on the switch member being arranged in position to prevent opening of the door 12 when the switch member is closed as seen in Fig. 3. Thus the switch member must be 70 opened into its position shown in Fig. 4 before the door can be opened into the position seen in Fig. 5, and when the parts are in the position shown in Fig. 5, the switch member cannot be closed as the rock arm 38 on the door is arranged in the path of movement of 75 the rock arm 39.

The switch arm 31 is concaved to permit the movement of the arm 39 on the door 12.

This box is particularly advantageous in 80 that both compartments are in the same plane so that the electrical appliances can be mounted on a common base and it is further advantageous in that it provides a particularly simple and efficient means for 85 making the device safe against careless attendants.

What I claim is:

1. A service box formed with an opening 90 in one side, a movable cover for the opening, a switch located in the box and including a movable member disconnected from the cover, and mechanism carried by the cover for operating the switch member said mechanism being movable with the cover 95 and comprising a rock arm connected to the switch member to transmit motion thereto and having means to interlock therewith to prevent movement of the cover when the switch is on and to move into a position to 100 detach said mechanism from the switch member upon opening movement of the cover when the switch is off, substantially as and for the purpose described.

2. A service box formed with an opening 105 in its front side, a movable cover for the opening, a switch mounted on the bottom of the box and including a hinged member and a bar remote from the axis of the switch member, and means carried by the cover for 110 operating the switch member including a rocking part mounted on the cover at one side of the switch member and arranged with its axis substantially in alignment with the axis of the switch member, and a rock 115 arm mounted on said part and having a portion extending laterally in a direction substantially parallel to the axis of the switch member and formed with a channel having its open side toward the axis of the switch member for receiving the bar and being movable into a position at approximately 120 a right angle to said open side when the switch member is open, substantially as and for the purpose set forth.

3. A service box formed with an opening 125 in one side, a movable cover for the open side, a fuse compartment and a switch compartment in the box beneath the cover, the cover being also formed with a door opening 130

- into the fuse compartment, a switch in the switch compartment comprising a movable member, and operating means for said member including means for preventing the removal of the cover when the switch is closed and permitting removal thereof when the switch is open, said door and the switch operating means having interlocking parts operable to prevent opening of the door when the switch is closed and to prevent closing of the switch when the door is open, substantially as and for the purpose specified.
4. A service box formed with an opening in one side, a movable cover for the open side, a fuse compartment and a switch compartment in the box beneath the cover, the cover being also formed with a door opening into the fuse compartment, a switch in the switch compartment comprising a movable member, and operating means for said member carried by the cover and including a part interlocking with the switch member when the switch is closed to prevent removal of the cover, and detachable from the switch member upon removal of the cover when the switch is open, said door and the operating means having interlocking parts operable to prevent opening of the door when the switch is closed and to prevent closing of the switch when the door is open, substantially as and for the purpose specified.
5. A service box formed with an opening 35 in one side, a fuse compartment and a switch compartment, a cover for the open side, having a hinged door opening into the fuse compartment, a switch located in the switch compartment and comprising a hinged member 40 having a bar extending substantially parallel to its axis, and operating means carried by the cover comprising a rock shaft arranged substantially in axial alignment with the axis of the switch member and extending through one side of the cover, and a rock arm mounted on the cover and having a portion extending parallel to the axis of 45 the switch member and formed with a channel opening toward the axis of the switch member, the channel receiving the bar, the door and the operating means having rock arms extending into each others paths and arranged to prevent opening of the door when the switch is "on" and closing of the 50 switch when the door is open.
- In testimony whereof, I have hereunto signed my name at Syracuse, in the county of Onondaga, and State of New York, this 4th day of February, 1916.
- CARL H. BISSELL.
